Patented Apr. 12, 1921.

Inventor:
Stephen A. Stilwell,
By John Elias Jones,
Attorney.

UNITED STATES PATENT OFFICE.

STEPHEN A. STILWELL, OF LEBANON, OHIO.

ADVERTISING NOVELTY.

1,374,687.

Specification of Letters Patent. Patented Apr. 12, 1921.

Application filed November 13, 1918. Serial No. 262,382.

To all whom it may concern:

Be it known that I, STEPHEN A. STILWELL, a citizen of the United States of America, and a resident of Lebanon, in the county 5 of Warren and State of Ohio, have invented a certain new and useful Improvement in Advertising Novelties, of which the following is a specification.

This invention relates to devices used in 10 advertising commodities and various business enterprises, and, more especially, to portable or movable independent inkstands used on tables, desks and like supports in hotels, offices and public places of advantage 15 to advertisers.

The invention herein consists of a portable slab or base having one or a plurality of panels arranged longitudinally across the fore part of its top surface in which cards 20 or the like containing advertising matter are inserted or placed so as to be exposed to ready view, an ink bottle or well inserted and suitably held in an opening made in one 25 of the rear corners of the said top surface of the base, and a series of longitudinal, parallel grooves or recesses made in the rear part of said top surface of the base convenient to hold pens or pencils used by the occupant of the independent table or desk on 30 which the combination advertising device herein is placed for use.

The actual details of structure will be 35 fully hereinafter described in connection with the accompanying sheet of drawings, in which—

Figure 1 is a perspective view of the portable independent advertising device embodying my invention herein in its preferred form;

Fig. 2, a transverse section taken on a line with the ink-well, showing the manner in which the advertising cards are held within the fore part of the base, free for ready exchange;

Fig. 3, a perspective view of a desirable form of locking ring or clamp used by me in detachably securing the ink-well in place in the opening made in the rear left-hand corner of the base; and—

Fig. 4, a perspective view of an unlocking ring for use with the said clamp shown in Fig. 3, for the release of the ink-well when desired.

1 indicates a rectangular slab or base made 55 of wood or other suitable material and having a sloping, fore upper-surface 2 in which

is provided an elongated opening 3 with a beveled edge 4, and such elongated opening further having a shouldered portion 5, approachable from the bottom of the base and 60 adapted to receive the outer edges of the advertising cards 6 for exposure to view within the said opening 3 that forms an attractive panel in the top surface of the said base.

A sheet or a series of sheets of glass 7 65 is preferably placed under the shoulder 5 ahead of the card or series of cards 6 and a backing 8 is placed in contact with the bottom or back of said card, or series of cards, as customary in the framing of pictures. 70 Nails 9 are used to secure the cards in place against ordinary removal or tampering therewith.

10 indicates each one of the corner feet for elevating the base 1 above the supporting surface of the separate, independent, supporting desk or table whereon the device is removably placed for use and advertising exposure.

In the said panel, shown in Fig. 1, I display 80 a series of three cards each of which is adapted to contain the desired advertising matter and for which the advertiser pays and thus makes the device self-supporting and without cost ordinarily to the proprietor 85 of the place where installed.

The rear portion 11 of the top surface of the base is flat and horizontal, and provided with three elongated recesses or semi-deep grooves 11^a, extended longitudinally along 90 the said flat surface from about the center to almost the extreme right-hand end of the said base 1, for use in containing pens and pencils and writing materials of that sort, the left-hand end of the said flat top 95 surface being provided with an orifice or opening 12, pierced through the material of said base, as best shown in Fig. 2, and an ink-well 13 of any desired or approved type being inserted in such orifice 12, the latter 100 being preferably supplied, however, with a flat ring or flange 14 that rests in a countersink or shoulder 15 made in the top of the said orifice, and pendent resilient arms 16 extending from said ring 14 down into the orifice part way through but slightly free from the side wall of the orifice so that they can be forced outwardly by the lower extension 17 of the ink-well and then with their lower 105 inwardly-turned ends 18 adapted to engage 110 the beveled groove 19 made circumferentially around the lower part of the ink-well above

the extension 17, all as best shown in Fig. 2, although the ring 14 and its resilient arms 16 are best shown in the detached view, Fig. 3. The said arms 16 effectively lock the ink-well in place in the orifice 12 and prevent its ordinary removal therefrom by the usual run of patrons of the place of installation of the device, and, in order to readily remove the ink-well for the purpose of 10 cleaning, refilling, or replacing, as the case may be, I provide a separate unlocking or releasing ring 20 that has a series of upturned extensions or arms 21, corresponding in number to the arms 16 of the locking ring 14, such releasing-ring 20 being inserted in the lower end of the orifice 12 and manipulated upwardly and circularly until the arms 21 forcibly engage the resilient arms 16, whereby the latter may be then 15 thrown outwardly from engaging-contact with the shoulder 19.

It is obvious that the sloping side 2 of the top surface of the slab or base 1 can be duplicated along the opposite side of the 20 flat or horizontal part 11 of said top surface, and to contain one or more panels for advertising matter for presenting to the view of those sitting at a table or desk that is used along both sides thereof.

I claim:—

As an improved article of manufacture, an advertising novelty and writer's companion for desk use and display, comprising a rectangular shallow slab having a flat bottom and short corner-supporting ball- 30 projections, a partially horizontal flat top or upper surface having a forwardly and downwardly inclined upper surface, an ink-well sunk in an orifice or cavity at one rear corner of said horizontal upper surface 35 of the slab, a series or multiple of parallel longitudinal grooves or elongated shallow cavities provided in said horizontal upper surface to one side of said ink-well and adapted to contain pens and pencils, an 40 elongated sight or opening provided in said inclined upper surface and adapted to accommodate one or more show-cards, and a removable sheet of glass in said sight to cover the said show-cards free for exchange- 45 removal when desired, the whole being adapted for varied use on a flat-top table or desk, to display said show-cards and to serve the otherwise useful purpose of conveniently holding ink and pens for the occupant of the desk, substantially as herein shown and described.

STEPHEN A. STILWELL.
